US00D944732S

(12) **United States Design Patent** (10) **Patent No.:** **US D944,732 S**
Sun et al. (45) **Date of Patent:** **** Mar. 1, 2022**

(54) **POWER SUPPLY**

- (71) Applicant: **Shenzhen Hello Tech Energy Co., Ltd.**, Shenzhen (CN)
- (72) Inventors: **Zhong-Wei Sun**, Shenzhen (CN); **Wei Bai**, Shenzhen (CN)
- (73) Assignee: **Shenzhen Hello Tech Energy Co., Ltd.**, Shenzhen (CN)
- (**) Term: **15 Years**
- (21) Appl. No.: **29/712,826**
- (22) Filed: **Nov. 12, 2019**

(30) **Foreign Application Priority Data**

- Aug. 8, 2019 (CN) 201930429618.3
- (51) LOC (13) Cl. **13-02**
- (52) U.S. Cl.
USPC **D13/110**
- (58) **Field of Classification Search**
USPC D13/103, 199, 107, 108, 110, 184, 104, D13/105, 106, 118, 119, 123, 133; D15/9; D14/432, 434

CLAIM

The ornamental design for a power supply, as shown and described.

DESCRIPTION

FIG. 1 is a top, front, left perspective view of a power supply, showing our design.

FIG. 2 is a right, rear perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines shown in the drawing are for the purpose of illustrating portions of the power supply that form no part of the claimed design.

1 Claim, 8 Drawing Sheets(56)
